UNITED STATES PATENT OFFICE.

SAMUEL M. BYRD, OF KOSCIUSKO, MISSISSIPPI, ASSIGNOR TO UNDERWOOD TYPE-WRITER COMPANY, OF NEW YORK, N. Y., A CORPORATION OF DELAWARE.

TYPE-WRITING MACHINE.

1,318,435.

Specification of Letters Patent. Patented Oct. 14, 1919.

Application filed January 4, 1918. Serial No. 210,352.

To all whom it may concern:

Be it known that I, SAMUEL M. BYRD, a citizen of the United States, residing in Kosciusko, in the county of Attala and State 5 of Mississippi, have invented certain new and useful Improvements in Type-Writing Machines, of which the following is a specification.

This invention relates to an improvement 10 in typewriting machines, and more particularly to mechanism for positioning the carriage in any selected column, in connection with the operation of spacing the paper for a new line of writing, although some features of the tabulating mechanism may be 15 used without line-spacing operations or mechanism.

This invention discloses a tabulating or column-selecting mechanism which may be 20 used to select rapidly the starting position of the platen for beginning a new paragraph. The selection of a column or carriage position may be made either with or without the line-spacing of the platen. As 25 the carriage is returned to commence a new line, the carriage may be stopped at the inset point, corresponding to the beginning of a new paragraph and at the new line ready 30 to write. The column selecting may be done either by a backward or forward movement 35 of the carriage according to the position thereof. The mechanism preferably includes a series of keys carried by the carriage, any one of which may be operated to move a stop carried by the carriage into a 40 position to engage a comparatively fixed stop carried by the typewriter frame, so as to obstruct the return movement of the carriage. This will limit the extent of return 45 movement of the carriage and thus determine the beginning of a new line.

The keys, when operated in returning the carriage and also determining the beginning of a new line, may operate the line-space 45 mechanism, as the line-space lever extends upwardly into the path of operation of the column-selecting keys.

The stops carried by the carriage and operated by the column-selecting keys are 50 double-acting and provided with two projections, one for engaging the fixed stops on the return movement of the carriage, as explained above, and the other for engaging

the fixed stops on the advancing movement of the carriage. That is to say, in addition 55 to positioning the carriage and returning it, the keys carried by the carriage may also be used to determine the position of the carriage when the latter is moved in an advancing direction. The determining of the 60 position of the carriage on a return movement is by an operation of one of the keys in the manner in which the line-space mechanism is usually operated to return the carriage. For a positioning of the carriage by 65 an advancing movement thereof, the keys carried by the carriage are moved in the opposite direction, so as to bring one of the projections, according to the particular key selected, in line with one of the fixed stops 70 on the typewriter frame. The movement of one of the keys in this direction does not drag the carriage along, but releases it from the escapement mechanism, so that the spring-barrel normally used to advance the 75 carriage causes the same to jump forward until the selected stops coöperate with each other to bring the carriage to a halt at the position selected.

During an advancing tabulating movement of the carriage, the actuated key is locked in operative position until the selected stops engage with each other. When the latter takes place, the key becomes released so that it may return to its normal 85 position, thus permitting the feed rack to drop back into engagement with the escapement pinion.

The fixed stops are on separate racks, arranged at different levels and secured to the 90 typewriter frame. The carriage-stops are in the form of pivoted double-acting dogs extending between the racks, on which the fixed stops are adjustably mounted. The obstructions on each dog, forming a stop, are 95 disposed on opposite sides of the racks, so as to be moved alternatively into the range of the fixed stop which coöperates therewith to limit the travel of the carriage in either an advancing or return direction.

Other features and advantages will hereinafter appear.

In the accompanying drawings, Figure 1 is a left end view, in elevation, of the top part of the typewriting machine, 105 showing the relation of tabulating mecha-

nism on the carriage to that on the typewriter frame.

Fig. 2 is a top plan view, with the left-hand end of the typewriting machine partly broken away to show the underlying structure. This view shows one of the column-selecting or position-finding keys as moved to a position for determining the selection of a column by an advancing movement of the typewriter carriage. In this view, the key has released the carriage from the escapement mechanism, so that it is traveling toward a point where the stop operated by the key will come into engagement with a fixed stop.

Fig. 3 is a view similar to Fig. 2, except that one of the keys has been operated in the opposite direction to the operation in Fig. 2, so that one of the carriage-stops has been moved in the opposite direction from that of Fig. 2, to enable it to engage an obstructing fixed stop as the key which brought it into play returns the carriage to the beginning of the next line. This key is also shown as having operated the line-space mechanism to rotate the platen for the next line.

Fig. 4 is an enlarged view, similar to Figs. 2 and 3. All of the column-selecting keys are shown in their inactive, intermediate position, with all of the projections on the carriage-stops clear of the range of obstruction of the fixed stops.

Fig. 5 is a detail view, looking from front to rear at one of the fixed stops, showing the means of adjusting it along its supporting rack, and also showing the relation of the obstructing projections on the corresponding carriage-stop to this fixed stop.

Fig. 6 is a vertical section, taken from front to rear through one of the fixed stops, and showing the manner of adjustably securing it on its rack, and the relation of two of the carriage-stops with respect to the fixed stop.

Considering more particularly the separate parts of this invention as embodied in the form shown in the drawings, 1 indicates a typewriter platen which is mounted to rotate by means of an axle 2 on a carriage 3. The carriage 3 has the usual step-by-step movement at the striking of the character keys (not shown), in a manner common to Underwood standard typewriters. This includes a rack 4, pivotally mounted on the carriage 3 and normally engaging a pinion 5, forming part of the escapement mechanism. This pinion 5 is connected by a one-way pawl-and-ratchet mechanism 6 fixed to a ratchet wheel 7. The ratchet wheel 7 is the escapement wheel and is controlled in its movements by the usual fast and loose dogs 7^a, which are oscillated at the operation of the character keys, so as to release the escapement wheel step by step. The carriage 3 and thus the platen 1 is given a

letter-feeding movement by the usual spring-barrel 7^b under the control of this escapement mechanism.

The platen 1 may be rotated major amounts by means of the usual hand-knobs 8, provided at the ends of the axle 2, and may also be moved line-space amounts by means of the line-space mechanism quite similar to that provided upon the standard Underwood typewriter. This line-space mechanism includes a line-space lever 9, which is provided with an arm 10 engaging a slide 11 to move the latter against the tension of a return spring 11^a, Fig. 4. The slide 11 is provided with a pawl 12, which engages and operates a line-space wheel 13 secured to the platen axle 2. The pawl 12 is arranged in a manner, not pertinent to this invention, to rotate the line-space wheel 13 and thus the platen 1 a distance of one or more teeth to give a variable line-space movement to the platen.

To return the carriage 3 for the beginning of a new line, and at the same time determine the initial, indented position of that line, as, for example, for a new paragraph, there are provided a plurality of keys 14, in this case shown to be mounted on the carriage 3. These keys are in the nature of column-selecting keys and they may determine the position of the carriage 3 for different zones or major columns when the carriage is moved either in an advancing or a return direction. When the position of the carriage is to be determined for a return movement, the keys 14 themselves may be used to return the carriage. The keys 14 are pivotally mounted at 15 on a compound bracket 16, extending rearwardly on the carriage 3. These keys are provided at their front ends with finger-pieces 17, having inscribed thereon the particular column which they determine, such as "1", "2", "3" and "4".

The line-space lever 9 has an operating handle 18, which extends up in the path of movement of the keys 14, so that when they are moved in a direction to return the carriage 3 they at the same time operate the line-space lever 9 to rotate the platen to a new line.

Each of the keys 14 is provided with a stop 24, which may be termed a "carriage-stop", in that the keys 14 are carried by the carriage 3. These stops 24 are shown in the form of dogs pivoted at 25 on their corresponding keys 14. A spring 26 is provided for each key 14 and its associated stop 24 tends to yieldingly hold the stop in a normal position relatively to the key, which is determined by a pin 27 engaging an arm 28 on the key 14. Each stop 24 has a pair of projections 29 and 30, which form obstructions to engage alternatively on opposite sides the fixed stops 31, according to

the direction of movement of the carriage and the character of operation of one of the keys 14. The projections 29 and 30 are abrupt on one side and cam-shaped on the other side. This enables them to be obstructed by the stops 31 when in their active positions and moving in one direction, and to yield to one side when engaged by the stops 31 and moving in the wrong direction.

10 The stops 31 are adjustably mounted on racks 32. There is one of the stops 31 on a corresponding rack 32 for each of the corresponding stops 24, and thus for each of the column-selecting keys 14. The stops 15 31 may be termed "fixed stops", in that after once adjusting them, they are fixed on the racks 32, which, in turn, are supported by the typewriter frame 33. The racks 32 are held in spaced relation by means of brackets 20 34, which have parallelly-extending reaches 35, on which the racks 32 are directly mounted. These reaches 35 extend toward the front of the machine, so that the keys 14 can extend between the racks 32, and 25 also so that the carriage-stops 24 can extend between the racks 32, and thus enable the obstructing projections 29 and 30 to engage the fixed stops 31 selectively on opposite sides.

30 The stops 31 are adjustable along the racks 32, one or all of which may be provided with a scale 36, so as to accurately determine the position of the stops 31 for different letter-space positions of the carriage 3. The under sides of the racks are provided with teeth, whereby the stops 31 may be locked in any adjusted position by means of latches 37, one of which is provided on each of the stops 24. The latch 35 40 37 is hinged at 38 to the body portion of the stop, and is normally held in the full-line, locked position shown in Fig. 6, by means of a spring 39. In this position a tooth 40 on the latch 37 engages between two teeth 45 of the rack 32. The latch 37 can be depressed to the dotted-line position of Fig. 6 to enable a stop 31 to be adjusted along the corresponding rack 32.

50 The projections 29 on the stops 24 are used to engage the fixed stops 31 at 41, whereby the stops 31 are extended to form a projection when the keys 14 are used to return the carriage and determine the position of the carriage during such return movement. The projections 30, on the other hand, are used to determine the position of the carriage during an advancing movement of the latter by engaging projections 42, one of which is provided on each fixed 55 stop 31 on the opposite side from the projection 41. When a projection 42 is used to determine the position of the carriage by an advancing movement of the carriage, the corresponding key 14 is moved to the 60 position illustrated in Fig. 2. When moved

in this direction, a cam 43, provided on each key 14, engages a vertical rod 44 extending between arms 45, 46, pivoted by a shaft 47, and forces the arms 45, 46 against the tension of a spring 48 from the Fig. 4 position to the 70 Fig. 2 position. The arm 45 engages an arm 49 provided on a key-lever 50. The key-lever 50 is used to raise the carriage rack 4 out of mesh with the pinion 5. Thus, when one of the keys 14 is moved to the 75 left, as shown in Fig. 2, it will operate the key-lever 50 to disengage the carriage from the escapement mechanism, so that the spring-barrel will be free to advance the carriage until its movement is obstructed. 80 The limit of movement will be determined by the particular key 14 operated in this manner, which brings its projection 30 to a position to come into engagement with the corresponding stop 31 which lies in the path 85 of travel of the stop 24. During this tabulating movement of the carriage, the actuated key is held in its ineffective position by the bar 44, which, it will be remembered, is common to all of the keys. This is done 90 by providing each key 14 with a depression 43^a at the end of each cam 43, into which the bar 44 may drop at the end of the effective movement of the key 14. When the projection 30 of the stop 24 engages with 95 the fixed stop 31, the impact of the carriage is sufficient to draw on the key 14 and release it from the bar 44, after which the bar 44 becomes effective through the intermediary of the spring 48 and the cam 43, with 100 which the bar 44 engages, to fully restore the key 14 to its normal or ineffective position.

The keys 14 are locked in their intermediate, idle position, with both of the projections 29 and 30 out of range of the stops 31, by means of detents 51. There is one of these detents for each of the keys 14. Each of the detents 51 is in the form of a strip of thin metal, having a raised portion 52 engaging in a socket 53 provided on the corresponding key 14.

Considering the operation of the device, each stop 31 is adjusted along its bar 32 to a letter-space position corresponding to a 115 point of a major column or zone of the carriage at which it is desired to stop the carriage when the corresponding key is operated. The keys 14 normally occupy an intermediate position, such as that shown in 120 full lines in Fig. 4, and may be shifted individually to either side of this neutral position to determine zonal positions of the typewriter carriage.

The keys may be used to determine automatically the indentation for a new paragraph. This takes place after a line is completed, and it is usually necessary to return the carriage so that one of the keys 14 may be operated to return the carriage and at the 125 130

same time determine the extent of return of the carriage. When one of the keys 14 is used in this manner, the particular key 14 operated will also operate the line-space lever 9 to advance the platen 1 a line-space. The operation of one of the keys 14 in the direction necessary to return the carriage brings the projection 29 on the corresponding stop 24 closer to the corresponding rack 10 bar 32, so that when the carriage 3 is returned the desired amount, the projection 29 will engage the projection 41 on the corresponding stationary stop 31, the latter obstructing the further movement of the stop 24, and thus the further movement of the carriage 3. Thus, the carriage will be returned to a new starting position, which will be short of the usual beginning of the line, and the platen will be line-spaced for 20 this new paragraph and the new line. After the carriage has been arrested in the selected position, the key is returned to its normal position through the intermediary of the line-space handle 18 by means of the line-space restoring spring 11.

In addition to determining the indentation for a paragraph automatically, the carriage may be positioned by the keys 14 to other zonal positions. There are four keys 30 shown and four of the pairs of stops, so that for a given setting of the stops 31, the carriage may be positioned by a single operation to any one of the four columns previously determined upon. This selection may be made by an operation of the keys 14 in returning the carriage, as above explained, and also may be made by an operation of the keys with an advancing movement of the carriage.

40 To select a position of the carriage for any particular zone or major column by an advancing movement of the carriage, the key 14, corresponding to this position, is shifted to a position, as illustrated in Fig. 45 2, such that it will operate the disconnecting mechanism for the escapement mechanism. This consists in the cam 43 shifting the rod 44 and the arms 45 and 46 to the position of Fig. 2, whereby the carriage-rack 4 will be lifted out of mesh with the escapement pinion 5. The carriage 3 is then drawn in an advancing direction by means of the usual spring-barrel until the stop 24, on the key 14 operated, is carried 55 forward sufficient to bring the projection 30 thereon into engagement with the projection 42 on the corresponding stop 31. Further movement of the carriage 3 will be obstructed at this time, so that the position 60 of the carriage will be automatically determined for a zone or column corresponding to the particular key operated. Thus, for any position of the typewriter carriage, any one of a number of zones or major 65 columns can be instantly selected, either by

a return or an advancing movement of the carriage, according to the particular position of the carriage and the particular zone or major column desired.

Variations may be resorted to within the 70 scope of the invention, and portions of the improvements may be used without others.

Having thus described my invention, I claim:

1. The combination with a typewriter 75 carriage, of a plurality of stops carried by said carriage, a plurality of fixed stops arranged at different levels, one individual to each of said carriage stops, and a plurality of keys on said carriage for shifting said 80 carriage stops into the range of said fixed stops.

2. The combination with a carriage, of a plurality of column-selecting keys carried by said carriage, an escapement mechanism, 85 connections whereby any operated key releases the carriage, a device for holding any operated key effective until the carriage is arrested, said keys adapted for also returning said carriage, and a plurality of co-operating stops controlled by said keys to determine the extent of movement of said carriage by said keys when operated.

3. The combination with a carriage, of a 95 platen on said carriage, line-space mechanism for said platen, co-operating stops for determining the position of said carriage for the beginning of a new line, and a key controlling the co-operation of said stops and engaging said line-space mechanism to both 100 return said carriage a selected amount and line-space said platen.

4. The combination with a carriage, of co-operating stops for determining zonal or 105 column positions of said carriage, a platen on said carriage, line-space mechanism for said platen, and for returning said carriage, and a series of keys arranged alongside of said line-space mechanism, engaging said line-space mechanism to operate the same, 110 and connected to control the co-operation of said stops to determine the positions of said carriage.

5. The combination with a carriage, of 115 column-selecting mechanism for said carriage having a plurality of keys mounted on said carriage to travel therewith, a platen on said carriage, and line-space mechanism for said platen, including a line-space lever arranged in the path of movement of said 120 keys, whereby said keys may operate said line-space mechanism at the same time that they determine a column position of said carriage, said line-space lever projecting beyond said keys, so as to enable said line-space mechanism to be operated independently of an operation of said column-selecting mechanism.

6. The combination with a carriage, of a 130 plurality of column-selecting keys on said

carriage, escapement mechanism for said carriage, means for advancing said carriage, releasing means for said carriage actuatable by said keys, means common to all of 5 said keys for locking any one of said keys in its actuated position, and means for releasing said actuated key from said locking means.

7. The combination with a carriage, of 10 column-selecting mechanism for said carriage, including a plurality of keys, each individual to a given column and shiftable in one direction to bring said carriage to a corresponding column from a position of 15 said carriage in advance of said column, and shiftable in the opposite direction to bring said carriage to the corresponding column from a position of said carriage in the rear of said column.

20 8. The combination with a carriage, of a column-selecting mechanism for said carriage, including a plurality of keys arranged at different levels and mounted to travel with said carriage, a platen mounted on said 25 carriage, and line-space mechanism for said platen, including a line-space lever having a handle extending vertically alongside of said keys and beyond said keys, whereby said handle may be operated solely for a 30 line-space movement of said platen, and also whereby any one of said column-selecting keys may concomitantly operate said line-space mechanism and determine a column position.

35 9. The combination with a carriage, of column-selecting mechanism for said carriage, including a plurality of keys on said carriage corresponding to different column positions of said carriage, escapement mechanism for said carriage, means for advancing said carriage, a key on said carriage for disconnecting said carriage from said escapement mechanism, so as to permit an advancing movement of said carriage, 40 45 connections enabling said last-mentioned key to be operated from any one of said column-selecting keys, and locking means for said column-selecting keys.

10. The combination with a carriage, of a 50 fixed bar extending parallel to said carriage, a stop on said bar, a key carried by said carriage, and a stop on said key traveling with said carriage, and arranged to engage said stop on said bar alternatively on opposite sides thereof, according to the direction of movement of said carriage in determining a position of said carriage.

11. The combination with a carriage, of a plurality of fixed bars arranged alongside 60 of said carriage, a plurality of stops adjustable along said bars, a key for each bar mounted on said carriage, and a stop controlled by each key co-operating with the stops on said bars to determine selectively 65 column positions of said carriage.

12. The combination with a carriage, of a plurality of bars arranged alongside of said carriage, stops adjustable along said bars, keys carried by said carriage, and stops operated by said keys extending on both sides 70 of said bars, and having projections disposed on opposite sides of said bars, so as to engage alternatively with said stops on said bars, whereby said stops on said bars and those operated by said keys may be used to 75 control the selection of the position of said carriage with a movement of said carriage, either in an advancing or a return direction.

13. The combination with a carriage, of a plurality of bars arranged alongside of said carriage at different levels, stops on said bars, a plurality of keys mounted on said carriage at different levels, and a plurality of stops, one on each of said keys, extending into juxtaposition with respect to said stops 80 on said bars, and movable by said keys into range of said stops on said bars, so as to limit the movement of said carriage to a position corresponding to the key operated.

14. The combination with a carriage, of a plurality of bars arranged alongside of said carriage, a stop on each of said bars having projections facing in opposite directions, a plurality of keys mounted on said carriage to travel therewith, and a plurality of stops, one pivoted on each of said keys and operable thereby, each of said key-stops extending between said bars and having projections facing in opposite directions on opposite sides of said bars, so as to engage alternatively the projections of said stops on said bars. 90 95 100

15. The combination with a carriage, of a plurality of column-selecting keys on said carriage, escapement mechanism for said carriage, means for advancing said carriage, releasing means for said carriage actuatable by said keys, means for locking any one of said keys in its actuated position, means for automatically releasing said actuated key 105 from said locking means when the carriage reaches its proper position, and means for restoring said key to its normal position after it has been released from said locking means. 110 115

16. The combination with a carriage, of a plurality of bars arranged alongside of said carriage, stops adjustable along said bars, column-selecting keys, and double-acting stops operated by said column-selecting keys 120 extending on both sides of said bars, so as to engage alternatively said first-mentioned stops on opposite sides, according to the direction of movement of said carriage, to determine positions of said carriage. 125

17. The combination with a carriage, of a plurality of bars arranged alongside of said carriage, stops mounted on said bars, a plurality of column-selecting keys, one for each of said bars, and a double-acting stop for 130

each of said keys extending between said bars, each having projections on opposite sides of said bars, so as to engage alternatively said first-mentioned stops from opposite directions, according to the direction of movement of said carriage.

18. The combination with a carriage, of a plurality of column-selecting keys on said carriage, escapement mechanism for said carriage, means for advancing said carriage, releasing means for said carriage actuatable by said keys, said releasing means being actuatable by said keys and serving as a lock for said keys to hold any one of the latter in its actuated position, and means for automatically rendering said carriage-releasing means ineffective to hold the actuated key, and effective to restore the actuated key to its normal position.

19. The combination with a carriage, of a plurality of column-selecting keys upon said carriage for arresting the carriage in selected columns, a line-space mechanism, an escapement device, and means whereby shifting said keys in one direction returns the carriage and operates the line-space mechanism, and shifting said keys in the other di-

rection releases the escapement mechanism, each key arresting the carriage at one point irrespective of the direction of operation.

20. The combination with a carriage, of a plurality of column-selecting keys upon said carriage for arresting the carriage in selected columns, a line-space mechanism, an escapement device, means whereby shifting said keys in one direction returns the carriage and operates the line-space mechanism, and shifting said keys in the other direction releases the escapement mechanism, each key arresting the carriage at one point irrespective of the direction of operation, and a separately-settable stop for each key to determine the column of arrest.

21. The combination with a carriage, of a line-space lever adapted to return said carriage to a given point, and a stop-controlling lever adapted to operate said line-space lever and make said stop effective to arrest the carriage at another point.
